UNITED STATES PATENT OFFICE.

WALTER C. FOELL, OF WATERBURY, CONNECTICUT.

CAP-CLOSURE.

1,391,538.

Specification of Letters Patent. Patented Sept. 20, 1921.

Application filed March 21, 1918. Serial No. 223,752.

To all whom it may concern:

Be it known that I, WALTER C. FOELL, a citizen of the United States, residing at Waterbury, in the county of New Haven and State of Connecticut, have invented certain new and useful Improvements in a Cap-Closure, of which the following is a specification.

This invention relates to improvements in closures for bottles and jars and it is the principal object of the invention to provide a novel form of cap closure adapted to be applied over the mouths of bottles and other receptacles and secured by crimping or like modes of distortion to the necks of the same and which, when desired, can be quickly removed therefrom but when engaged with the bottle will serve as a highly efficient and positive seal therefor.

Other objects will be in part obvious and in part pointed out hereinafter.

The improvements in the details and arrangement of parts will be apparent from an inspection of the accompanying drawings, in connection with the specific description hereinafter contained, and wherein the preferred embodiment of the invention is disclosed for the purpose of imparting a full understanding of the same.

In the drawings:

Figure 1 is a side elevation of the improved cap closure as applied to a portion of a bottle neck,

Fig. 2 is a vertical section therethrough,

Fig. 3 is a vertical section through the cap showing the relative arrangement of the same and the closure disk before the lower portion thereof is crimped, and

Fig. 4 is a fragmentary horizontal section through a portion of the cap and the bottle neck showing the same crimped.

Having more particular reference to the drawings, in connection with which like reference characters will designate corresponding parts throughout the several views of the drawings, 1 represents the neck of the bottle, 2 the usual curved shoulder formed thereon directly below the mouth of the same and 3 the curved beading formed upon the upper end of the same adjacent its mouth; this construction being common in connection with the manufacture of bottles for containing different forms of beverages and the like.

The improved closure comprises a cap designated in its entirety by the numeral 4,

the intermediate portion of the annular sides thereof being crimped to form an annular inwardly extending rib 5, while the lower portion of the cap sides are adapted to be connected or engaged over the curved beading 3 by crimping as indicated at 6 or by other suitable forms of distortion.

A sealing disk 7 is provided and is adapted to be arranged over the mouth of the bottle neck 1; the marginal portion of said disk extending for a distance onto the curved beading 3 in order that the slanting face of the rib 5 formed in the annular sides of the cap 4 may be engaged therewith at the outer edge thereof and as a consequence, secured in position over the bottle neck mouth when the lower portion of said cap is crimped or otherwise distorted as at 6 in order to insure engagement between the same and said curved beading 3. With the cap thus applied over the bottle neck mouth, it will be readily understood that the bottle will be efficiently and positively sealed, thus, permitting the contents of the same to be effectually preserved.

Attention is directed to the fact, that the upper portion of the closure cap 4 is extended for a distance above the bottle neck, as clearly shown in the Figs. 1 and 2. Hence, when it is desired to disengage the closure cap from the bottle neck, it is only necessary to sharply or abruptly tap the top of the closure cap, thereby forcing the same downwardly and causing an outward riding engagement of the slanting face of the rib 5 with the disk and the beaded portion 3 and in consequence causing the annular sides of the cap to be moved outwardly. Such downward movement of the cap will also cause the crimped portion of the annular sides thereof to ride over the curved shoulder 3 and as a consequence, the crimped portion 6 thereof will be spread sufficiently to allow the closure cap to be freely withdrawn from engagement with the bottle neck. The circular side wall of the cap 4 lying between the rib 5 and closed end is of uniform diameter throughout thus providing a rightangular corner which is disposed so prominently that it may be conveniently struck against a wall or other object to remove the cap from the bottle.

From the foregoing, it will be understood by persons skilled in the art that I have provided an exceedingly cheap, simple and efficient form of bottle closure and one which

by reason of its construction may be quickly and readily disengaged from a bottle neck, thus, saving considerable time and quite often, preventing the wasting of the contents of the bottle or the fracturing of the bottle neck in attempts to remove the closure therefrom.

It is of course to be understood, that my improved cap closure may be adapted for 10 engagement with any form of bottle or jar having the neck thereof formed with curved engaging surfaces, whereby the lower portion of the cap will be spread upon downward movement of the same over said neck.

15 Further, the cap may be formed of any suitable material, such as sheet metal or the like, such as conditions or preference may dictate.

As indicated, I do not wish to be understood as confining the invention to the particular embodiment chosen for illustration herein, nor to the exact construction, arrangement and adaption of parts shown

and described, but I reserve the right to make any changes and alterations that fairly fall within the spirit and scope of the invention. 25

I claim:

The combination with a bottle having an outwardly directed annular bead at its mouth and an annular enlargement next the 30 bead, of a cap comprising a cylindrical body closed at the outer end and with an inwardly directed rib intermediate the ends, the portion of said cap between the rib and its open end adapted to be crimped into the space between the bead and the enlargement to lock the cap in position, the cap being detachable by pressure applied to the cap longitudinally of the bottle to force the rib over the bead and the crimped portion over the enlargement. 35 40

In testimony whereof, I affix my signature hereto.

WALTER C. FOELL.
